UNITED STATES PATENT OFFICE.

ARTHUR F. WELLS, OF SAN FRANCISCO, CALIFORNIA, ASSIGNOR TO ADJUSTABLE WRAPPING MACHINE COMPANY, OF SAN FRANCISCO, CALIFORNIA, A PARTNERSHIP CONSISTING OF NATHAN SCHILLER AND C. A. PETTERSON.

PACKAGE-WRAPPING MACHINE.

1,266,085.

Specification of Letters Patent. Patented May 14, 1918.

Application filed May 10, 1916. Serial No. 98,553.

To all whom it may concern:

Be it known that I, ARTHUR F. WELLS, a citizen of the United States, residing at San Francisco, in the county of San Francisco, State of California, have invented a new and useful Package-Wrapping Machine, of which the following is a specification in such full and clear terms as will enable those skilled in the art to construct and use the same.

This invention relates to a package wrapping machine and its object is to produce a machine which will be simple and easily operated, and which will wrap a parcel and seal the wrapper on the ends thereof in a single operation, the packages being discharged from the machine ready to be packed into boxes for shipment.

An object of the invention is to provide means whereby the paper to be wrapped around the parcels may be more certainly directed into the position it is to occupy just prior to the time the package is pushed against the same, a suitable receiving table advancing each time a fresh sheet is to be placed in position.

Another object of the invention is to provide means whereby the packages may be sealed as they are discharged from the machine.

Another object of the invention is to provide means whereby the machine will be generally operated only when a package is placed therein, the major portion thereof being out of operation unless said package is passing through the machine in its travel.

Other objects of the invention will appear as the description proceeds.

An embodiment of the invention is shown in the drawing in which the same reference numeral is applied to the same portion throughout, but I am aware that there may be many modifications thereof,

Figure 1 is a side elevation of the complete machine,

Fig. 2 is an end elevation of the complete machine looking in the direction of the arrow 2 on Fig. 1,

Fig. 3 is a plan view of the movable folding carriage as it appears just before receiving a package to be wrapped,

Fig. 4 is a side elevation of the machine looking in the opposite direction from Fig. 1,

Fig. 5 is a view in end elevation of the machine looking in the direction of the arrow 5 on Fig. 4,

Fig. 6 is a detail view in plan of certain of the operating cams,

Fig. 7 is a detail view of the paper receiving table,

Fig. 8 is a plan view of the complete machine,

Fig. 9 is a vertical sectional view of the complete machine on the line 9-9, Fig. 8,

Fig. 10 is a plan view of that portion of the machine below the paper supply roll, portions of the machine being removed for purposes of illustration,

Fig. 11 is a view in rear elevation of the parts of the machine below the paper feed roll,

Fig. 12 is a plan view on the line 12-12, Fig. 11 showing the arms supporting the bottom folding device,

Fig. 13 is a detail view in elevation of the levers for starting the machine when a package is placed therein to be wrapped,

Fig. 14 is a plan view of the tripping device on the drive wheel,

Fig. 15 is a vertical sectional view of the paper feed roll,

Fig. 16 is a view in end elevation of the paper feed roll and pawl for causing the same to rotate in one direction,

Fig. 17 is a view on the line 17-17, Fig. 15 illustrating the driving mechanism for the paper feed roll,

Fig. 18 is a plan view of a portion of the discharge conveyor,

Fig. 19 is a side elevation partly in section of the discharge conveyor,

Fig. 20 is a view of a portion of the discharge conveyor looking in the line of motion thereof,

Fig. 21 is a view in end elevation through the discharge chute through which the packages are passed and showing the sealing device for sealing the ends thereof,

Fig. 22 is an end elevation of the package as it appears when the first fold has been made therearound,

Figs. 23, 24 and 25 are perspective views illustrating three different steps in the folding operations following the first folding shown in Fig. 22,

Fig. 26 is a perspective view of the completely folded package,

Fig. 27 is a vertical sectional view through a completely folded package showing the relation of the covering to the package and the direction of motion of the package 5 through the discharge chute being indicated by the arrow,

Fig. 28 is a diagrammatic view of the wiring for the operating of the motor and the electric heater, and

10 Fig. 29 is a plan in section of the receiving end of the discharge chute.

The numerals 1 and 2 indicate rectangular frames forming the sides of the machine. These frames are suitably secured to two 15 bases 3 and 4, which bases serve to connect the side frames at the bottom and to support them at a convenient elevation above the floor. Rods 5, 6, 7 and 8 at the corners of the frames serve to hold them rigidly in 20 the desired position parallel to one another and at such a distance apart as is necessary to permit the assemblage therein of the several working parts of the machine. Each of the frames is provided with a horizontal 25 cross piece about midway the height of the frame as indicated at 9 and 10, said cross pieces serving to support the bearings 11, 12, 13, 14, 15 and 16.

The bearings just mentioned support 30 three parallel horizontal shafts 17, 18 and 19 which are the main driving shafts of the machine. These shafts are connected together and are driven in unison by means of three gears 20, 21 and 22. The center shaft 35 18 also has a gear 23 thereon which is in mesh with a smaller gear 24 on a shaft 25 which shaft also has a larger gear 26 thereon, the larger gear being in mesh with a small gear 27 on the shaft 28, the latter 40 shaft also carrying a pulley 29 around which the belt 30 from the motor pulley 31 extends.

The result of the construction just outlined is that the shaft 18 as well as the 45 shafts 17 and 19 which are connected therewith by equalized sized gears are driven at a very slow rate of speed from the motor and all of said shafts are driven at the same rate of speed. The gear 21 is loose on the shaft 50 18, while at the side of the gear there is a disk 32 which is rigidly secured to said shaft and has a roller 33 on the side thereof, said roller being for the purpose of engaging a hook 34 pivoted to one of the spokes 55 of the gear 21 at 35 for the purpose of driving the gear 21 when necessary. The opposite end of the hook is pivoted to a lever 36 which has a curved portion 37 which engages a plate 38 when it is desired to operate the machine, as will be later explained.

The wheel 21 carries a spring 39 which normally holds the lever 36 in a position for the hook 34 to engage the roller 33, but as said lever is carried around its heel piece 60 65 will contact with the plate 38 which will

lift the hook so the roller cannot engage it. As soon as the parcel has been placed in position on the trip 262, the plate 38 will be pushed out so the roller can engage the hook on its next revolution. The machine is at 70 rest except when the trip 262 has been operated.

At the top of the frames there is a plate 40 which serves to connect the frames together and to form a sort of support for 75 the carton feeding plunger 41 as well as a support for the legs 42, 43, 42' and 43' carrying the work table 44. Supported on the cross bars 45' and 46' is the plate 40 from which cross bars depend four bolts 45, 46, 80 47 and 48, which bolts carry cross bars 47' and 48' and a horizontally extending chute 49, said chute also being supported at the front end by means of two brackets 50, 51 connected with four brackets 52, 53, 54 and 85 55. The brackets just mentioned have suitable bearings 53' and 55' at their outer ends for a shaft 56 while at the other end of the chute 49 there are two downwardly depending arms 58, 59 which have a shaft 60 90 journaled at their lower ends.

The shafts 56 and 60 are each provided with two sprocket gears as indicated at 91, 61, 62, 63 and 64, over which gears sprocket chains 65 and 66 pass, said sprocket chains 95 carrying suitable flights 67 for the discharge from the machine of the folded package. In order to prevent the flights from dropping down on the other parts of the machine the chute 49 has six depending links 100 67, 68, 69, 70, 71 and 72 which support two rails 73, 74 for the flights of the chains to ride back on, and in order to hold the flights in an upright position as they pass through the chute each flight is provided with two 105 tail-pieces as indicated at 75 to slide on the chute bottom 76, which latter is supported by three bars 76^a, 76^b and 76^c.

Just in front of the plunger 41 there are two angular posts 77, 78 which support a 110 transverse partition 79, which forms the registering device for placing the packages in the machine. A pair of guides 80, 81 are connected to the posts 77, 78 in order to guide the plunger 41. Just in back of the 115 transverse partition 79 there is a chute having partitions 82 and 83 through which the paper sheet 84 passes after it leaves the feed roll 85. The feed roll 85 and paper supply roll 86 are supported on suitable standards 120 87, 88, 89 and 90, which standards are in turn supported on two frames 91, 92 resting on the top of the sides frames 1 and 2 near one end thereof.

The paper feed roll 85 is journaled on a 125 shaft 93 and has a pinion 94 thereon which is in mesh with a vertically movable rack bar 95. The rack bar 95 is held in engagement with the pinion 94 by means of a roller 96 journaled on a pin 97 carried by a bracket 130

98, which bracket is supported on the journal post 90 which carries the paper feed roll. The pinion 94 is loose on the shaft 93 and is secured to the collar 93' which carries a pawl 99 which engages a pawl wheel 100 so that the feed roll is rotated in but one direction and then only enough to deliver paper for one wrapper. In order to insure the feed roll having a good tractive effort it is provided with a friction surface 101 and a small roller 102 supported by links 103, 104 bears on the paper sheet as it passes over the feed roller to hold the sheet in contact therewith, so that the proper amount of paper will be fed down into the chute formed by the plates 82, 83 whenever a parcel is to be wrapped, and springs 105, 106 hold the roller 102 down tightly as may be required.

20 In back of the paper supply roll 86 there are two pivoted arms 107, 108 carrying a plate 109, which plate is held normally in contact with the paper on the paper supply roll by means of springs 110 and 110', the object being to prevent the paper supply roll from unrolling too rapidly. When it is desired to disengage the brake from the paper supply roll a hook 112 pivoted on top of the support 113 is engaged with a pin 25 on the arm 107, thereby preventing the plate 107 from coming in contact with the paper on the paper roll.

25 The frames 91, 92 are provided with guide ways as indicated at 114, 115, said guide ways providing a support and path of travel for the knife 116, which knife projects through slots in the plates 82, 83 at 117 when the paper strip is to be cut off.

30 The horizontal support 118 which carries the journal posts 89, 90 has depending therefrom an L shaped bracket 119 which has a slot for a rearwardly extending bar 120, which bar is for the purpose of moving the knife forward when the lever 121 contacts therewith at the proper time. A lug 122 is secured to the knife and depends therefrom and carries a roller 123 which contacts with a spring 124. An auxiliary spiral spring 124' assists the spring 124 in pushing the knife back after the paper has been cut.

35 Situated below the knife is the parcel carrier, said parcel carrier comprising a horizontal bottom 125 connected with a horizontal top piece 126 by means of two vertical side pieces 127, 128, these four parts forming a horizontally extending open ended chute into which the parcel to be wrapped is pushed. The parcel carrier is provided 40 with a pair of slidable plates 130, 130' which are connected together at their back ends by means of bars 132, 133 and at their front ends by a bar 131 against which the parcel to be wrapped is pushed when it is pushed 45 into the parcel carrier. The package car-

rier slides vertically on two guide bars 131^a, 131^b, guides 132^a, 132^b being secured to the carrier sides.

The bars 132, 133 are connected to a rearwardly extending bar 134. At the back end 70 the bar 134 is provided with a depending lug 135, a small stiff spring 136 depending over the end of the bar 134 to prevent it from moving rearwardly except when pushed back by the parcel and then under 75 some friction. The spring 136 is secured to the top of two bars 137, 138 which are secured to the bottom plate 125 of the package carrier and which project therefrom and form a guide way for the bar 134.

80 The plates 130, 130' carry depending pins 140, 141 which project through slots in the plate 125 and afford means whereby said plates are guided in their travel in addition to the guiding means afforded by the 85 plates 137, 138. The plates 130, 130' are also provided with pivoted levers 142, 143, the heels of which strike the pins 141, 140 while the longer ends thereof strike a pin 144 projecting upwardly from the bottom 90 plate 125. Springs 145, 146 connect the levers 142, 143 with the plates 130, 130' in order to draw the plate 131 against which the parcel is pushed back into the parcel carrier when the parcel has been pushed therefrom into the discharge chute. It will be observed that the plate 131 moves off the plate 125 to the right Fig. 9 not less than the width of the carton, and as the pin 144 is fixed in position said levers 142 and 143 100 and springs 145, 146 will return the plate and attached parts as soon as they are released.

95 At the sides of the bars 130, 130' are two upwardly projecting corner angles 150, 151 105 which are secured to the bottom plate 125 and which hold the end folding plates 152, 153 in their proper position. The end folding plates 153, 152 have inclined ends as illustrated at 154, 155 for the purpose of 110 forming one of the folds of the paper on the parcel and they are connected together at their back ends by means of a U shaped plate 156 which is in turn connected to a rearwardly connecting bar 157, said bar 115 having a pin 158 projecting therefrom which extends into a slot formed by two bars 159, 160 to act as a guide.

120 The bars 159, 160 are supported by two cross bars 161, 162, the bar 161 being so positioned that the pin 158 is moved forwardly when it is passing the same so that it does not contact therewith. The bar 157 is provided with a short link 163 which is pivoted thereto and which link is pivoted to a lever 125 164, (note Fig. 10) said lever being pivoted to a backwardly extending arm 165 on the package carrier and projecting into a cam groove 166 in a plate 167 secured to the frame 1.

Depending from the package carrier are two lugs 172, 173, which lugs are connected by a shaft 174 and which shaft supports four arms 175, 176, 177 and 178, said arms 5 being rigidly secured thereto and to each other. Springs 179, 180 bear on the underside of the package carrier and on top of the arms 175 and 178 to hold them normally down. At the front of the package carrier 10 there are two depending guide members 181, 182 which carry slide bars 183, 184, said bars being fastened respectively to the arms 175 and 178.

The upright portions of the frames 1 and 15 2 and just out of contact with the largest operating cam carry a cross bar 185, which cross bar supports a stop 186 which the two arms 176, 177 contact with when the package carrier descends for the purpose of making 20 the bottom fold on the package.

The package carrier is supported by two links 186', 187 connected at their lower ends to levers 188, 189 on a transverse shaft 190, arms 191, 192 carrying balance weights 193. 25 194 to assist in raising the carriage, springs 195, 196 being also used for the same purpose. The shaft 190 is also provided with an arm 197 rigidly connected therewith which has a roller 198, said roller being engaged 30 by a large cam 199 on the shaft 17.

Pivoted on a bar 200 at the bottom of the frames 1 and 2 is a long lever 201 which is held normally in the position shown in Fig. 9 by means of the spring 202. This lever 35 extends up far enough to contact with the end of the bar 120 which operates the knife, and it is provided with a pin 203 which contacts with the heel piece 135 of the bar 134 when the parcel is to be pushed out of 40 the package carrier.

The shaft 17 carries three cams 199, 205 and 206. The cam 199 operates the lever 197, which lever depresses the package carrier after the package has been pushed 45 thereinto and allows it to be raised with the force supplied thereto by the springs and counterbalances. The cam 205 operates on a roller 207 carried by an arm 208 rigidly connected with the long lever 201. The cam 206 operates on a roller 209 carried by a lever 210 pivoted at the opposite end to a bar 211 supported by the side frames 1 and 2. The bar 210 is held normally in the position shown in Fig. 9 by means of the long 50 spiral spring 212. The bar 210 strikes a stop screw 210' on its up strike which is carried by a bar 210a.

Pivoted mounted on the shaft 60 supporting the sprocket wheel 61 is a lever 213, 60 (see Figs. 7 and 9) the lower end of which has a projecting portion 214 in contact with a roller 215 on the lever 210. A spiral spring 216 at the upper end of the lever 213 holds it normally against the roller 215 65 and it carries a rod 217 which engages de-

pending lugs 218 on the paper receiving table 219. The paper receiving table rests on a partition 220 at the receiving end of the discharge chute and is carried by two guide rails 221 and 222. The table 219 moves 70 forward when the paper is about to be fed thereon to prevent the paper from passing down into the space previously occupied by the box carriage. The rails 221, 222 are supported at one end by suitable brackets 75 on the top of the partition 220 and at their other end they are supported by legs 223, 224 which rest on the top of the discharge chute. The rails 221, 222 are provided with overlapping arms 225, 226 which bear on 80 the plate 219 and hold it in the proper position as it is operated by the lever 213.

The shaft 19 is provided with a cam 227 which bears on a roller 228 on the upper end of a lever 229 pivoted at the bottom of the 85 machine and on a bar 230, which bar also carries levers 231, 231' connected to short links 232 and 232' at its upper end, said links being pivotally connected with the package feeding plunger 41. The precise 90 position of the plunger 41 is determined by means of a set screw 233 carried by the lever 229 and which bears on a bar 234 connected with the levers 231, 231'. Then plunger 41 is retracted by means of stiff springs 256, 95 256' which are connected with the side frames 1 and 2 and with the levers 231, 231'.

The lever 210 is connected with the rack bar 95 for the purpose of operating the 100 paper feed roll each time a package is forced into the package carrier.

The discharge chute 49 has two plates 235, 236 connected thereto at its inlet end. These plates are flaring on the receiving end and 105 have their upper corners curved to permit the upper unfolded flap of the paper to pass thereover until said flaps come into contact with the side of the chute just outside these two plates, whereupon the final fold is produced, the upper flaps being bent down over the ends of the parcel.

Since the parcels are ordinarily wrapped with wax paper of some kind it is possible to seal them with heat and flat electric heaters 115 238, 239, 240 are provided which seal the 44 ends of the parcel and also seal the top fold as they pass through the discharge chute. The shaft 56 at the end of the discharge chute is provided with a sprocket wheel 250 120 over which a chain 251 passes and in order to depress the chain below some of the other parts of the machine a sprocket wheel 252 is provided, under which the upper run of the chain passes. Since the chain must be driven 125 in the direction of the arrow, Fig. 4, it is necessary to drive it from the center shaft 18, that shaft being provided with a sprocket wheel 253 for that purpose. The shaft 19 is provided with a sprocket wheel 254 which is 130

loosely mounted thereon and under which the lower chain 251 passes, the object being to prevent the chain from dragging on the underside of the shaft 19.

5 Since it is desired to feed the paper through the machine and to operate the plunger only when a parcel is in position to be fed thereinto, the spring 39 and pivoted hook 34 are so arranged that when the heel 10 piece 37 of the lever 36 strikes the plate 38 the hook will be lifted so that it will not be engaged by the roller 33, but as soon as the plate 38 is pushed out of engagement with the heel piece 37 the spring 39 pushes the 15 hook down low enough so that the plate 38 will engage the same and cause the wheels to make one revolution, and if a parcel has been placed in the feeding position it will continue to run. The plate 38 is pivoted on 20 a longitudinally extending bar 257 and it has a small weight 258 which tends to hold it in position to engage the heel piece 37 whenever a parcel is not placed in the feeding position.

25 The plate 38 is connected to a link 259, which link is connected to a lever 260, said lever being pivoted at its center on a bracket 260' and connected at its upper end to a bell crank lever 261 on the portion 262 which 30 projects above the feed table on which parcels are placed ready for feeding. It is sometimes necessary to operate the machine without having a parcel pass therethrough and in order to provide convenient means for 35 this a lever 263 is provided which can be operated by hand to shift the plate out of the path of the heel piece 37 of the lever 36. This lever is pivoted on the frame of the machine at 264 and has a link 265 which connects it with the plate 38.

The machine is driven from the motor 266 by means of a belt 30 and a switch 268 is provided for controlling the motor circuit, while a switch 269 is provided for controlling the heating circuit, suitable cables running from said switches to the heater and motor. On the front of the machine a resistance box 270 is provided to control the heat of the heaters to which the electric 50 cables run.

In Fig. 28 there is shown a diagrammatic view of the electric wiring in which the numerals 272, 273 indicate the inlet wires and 274 a main switch. From the switch 274 wires 275, 276, 277, 278, and 279 extend to the switch, resistance box and electric heaters. From the switch 269 wires 280, 281, 282, 283 extend to the switch 269, motor and return to the main switch 274.

60 The character of the folding operations is illustrated in Figs. 22 to 27 inclusive in which Fig. 26 indicates the completely folded package and Fig. 22 indicates the condition of the package when being first pushed into 65 the package carrier. The numeral 284 indi-

cates the package, 285 indicating the wrapper therefor. It will be observed that the wrapper when in position to be carried into the package carrier around the package lies on the paper table 219 and stands in front 70 of the package so that when the package is pushed into the package carrier the paper is folded at two corners, one short fold at the top of the package and a longer fold at the bottom as indicated at 286 and 287 respectively. As soon as the fold shown in Fig. 22 has been made the package carrier begins to move down and as it does so the cam 166 forms the fold shown at 288, the fold at 289 having been started as soon as the package 80 carrier begins to move down. As soon as the fold 288 has been made the cam 166 moves those folding plates out together thereby leaving space for the plates 183, 184 to come up and make the fold 290 at each end of the 85 package and these plates remain in position until the package has been pushed into the discharge chute, the first movement of which produces the fold at 291 and a further movement of which produces the fold across the 90 end at 292, the plates 235, 236 forming said fold 292, the only remaining fold then is the top fold 294 at each end of the package and this fold is produced by that portion of the wrapper which passes over the top of the 95 plates 235, 236, the discharge chute sides 235', 236' turning said flaps down.

The complete operation of the machine is as follows: With the motor running the chain belts 65 and 66 run continuously and 100 so long as no package is placed in the machine the hook 34 will be lifted over the pin 33 each time the lever 37 comes to the plate 38 so that none of the feeding or other machine operations will take place. However, 105 as soon as a package has been placed in position between the chute sides 77, 78 the package will bear on the trip lever 262 thereby moving the plate 38 out so that the lever 37 will not strike it as it passes around, whereupon the pin 33 will carry the wheel 21 around as the other wheels will also be carried. Prior to this time the paper will have been placed by hand between the two partitions 82, 83 and run down far enough to 110 cover the package. This sheet will then be cut off by the hand operation of the knife 116, whereupon the machine is ready to proceed with its work.

115 The first step will be for the plunger 41 120 to push the package into the package carrier against the plate 131 carrying the wrapper along with it. As soon as the parcel has been pushed into the package carrier the plunger 41 will be retracted and the lever 201 will begin to move forward as the package carrier begins to move down. While the package carrier is moving down the cam 166 operating on the rod 164 will cause the two plates 154, 155 to form the 125 130

first end fold by moving forwardly. As the package carrier moves to the bottom of its travel these two plates are retracted to their original position and the stop 186 causes 5 the two plates 183, 184 to move up and form the bottom fold and while the descent is being made the lever 210 will move down, thereby bringing the rod 95 down and moving a fresh length of paper into position. 10 At the same time that the paper is being moved down the paper receiving table 219 is moved forwardly by the cam 214 passing over the top of the roller 215 and as soon as the return stroke is made the receiving 15 table for the paper will move back to the position shown in Fig. 9 with the length of paper thereon, while at the bottom of its travel the package carrier will have the package therein pushed into the discharge 20 chute by the pin 203 contacting with the depending lug 135 on the plate 134 and at this same time the lever 121 will contact with the plate 120 cutting off the length of paper that has just been fed down to the receiving carriage. 25 As soon as the paper has been cut and the parcel pushed out of the parcel carrier the lever 201 will be allowed to return to the position shown in Fig. 9.

As the parcel is pushed into the discharge 30 chute the next to last fold on its forward edge is produced by the plates contacting with the plates 235, 236, the upper edges of the wrapper passing over the top of said plates and being pushed downwardly by the 35 outer edges of the discharge chute as indicated at 235' and 236'. The parcel is pushed far enough into the discharge chute for the flight bars 67 to contact therewith and push it on out to a suitable receiving table at the 40 end of the machine and as it is pushed through the machine it will pass the heaters which will cause the paraffin in the wrapper to be heated sufficiently to seal the several folds together.

Having thus described my invention what I claim as new and desire to secure by Letters Patent of the United States, is as follows, express reservation being made of permissible modifications:

50 1. A package wrapping machine comprising a movable package carrier, means to push the package into said carrier, paper feed rolls, means to feed a strip of paper across the end of the package carrier so that 55 when a package is pushed therewith the paper will be pushed along therewith, a longitudinally reciprocable inclined paper receiving table, and means to fold the paper strip around the package.

50 2. A package wrapping machine comprising a vertically movable package carrier, a paper supply and paper feed roll, means to feed a length of paper in front of the pack-

age carrier, means to push a package and a strip of paper into said package carrier at 65 right angles to its line of movement, means to cut said paper strip into determinate lengths, an inclined laterally movable paper receiving table upon which the paper is delivered for the next parcel to be wrapped, 70 and means to fold the paper over the ends of the parcel.

3. A parcel wrapping machine comprising a vertically movable package carrier, paper feed and paper supply rolls, means to 75 cause a determinate length of paper to be fed in front of the package carrier, a movable abutment in the package carrier against which the strip of paper and the package are to be pushed, means to push the package 80 into the package carrier at right angles to its line of movement, movable plates supported by the package carrier for forming two end folds at each end of the package, a discharge chute into which the package is 85 pushed after being moved into a suitable position by the package carrier, said discharge chute having plates for forming the remaining two end folds at each end of the package, a receiving table, and a movable 90 knife for cutting said strip of paper into determinate lengths.

4. In a packaging machine, a package carrier, paper feed and supply rolls, means to feed determinate lengths of paper in front 95 of the package carrier, a plunger to push the packages and strip of paper into the package carrier, means to move the package carrier to form one fold of the paper across the package, a paper receiving table, 100 means to move the paper receiving table forwardly over the package carrier and to retract the same after the paper has been fed, an abutment in the package carrier against which the package is pushed, means to push said abutment out of the package 105 carrier into the discharge chute, means to return the abutment to the package carrier, and means to fold the remaining ends of the paper strip across the ends of the package 110 as it is being pushed into the discharge chute.

5. In a parcel wrapping machine, a feed table, a vertically movable parcel carrier, a plunger in the parcel carrier, means to hold 115 said plunger normally in an intermediate position, a plunger to push the package against the plunger in the parcel carrier, a link and cam mechanism to operate the carrier, and a pair of vertically movable end 120 plates on the carrier to fold the ends of the wrapper across the parcel.

6. In a parcel wrapping machine, a feed table, a parcel carrier, a plunger carried thereby, a link and cam mechanism for mov- 125 ing said parcel carrier vertically, means to

hold said plunger in an intermediate position, a feed plunger to push a parcel into the carrier, a lever adapted to push the carrier plunger and the parcel out of the carrier into the discharge chute, vertically movable plates to produce certain of the end folds of the wrapper on the parcel when the

parcel is in the carrier, and double sides at the mouth of the discharge chute for producing the remaining end folds on the parcel. 10

In testimony whereof I have hereunto set my hand this 3rd day of May, A. D. 1916.

ARTHUR F. WELLS.
